UNITED STATES PATENT OFFICE.

HAROLD C. M. CASE AND WILBUR J. CARMICHAEL, OF URBANA, ILLINOIS.

STOCK-FEEDING DEVICE.

1,346,878.

Specification of Letters Patent. Patented July 20, 1920.

Application filed September 7, 1917. Serial No. 190,187.

To all whom it may concern:

Be it known that we, HAROLD C. M. CASE and WILBUR J. CARMICHAEL, citizens of the United States, residing at Urbana, in the county of Champaign and State of Illinois, have invented certain new and useful Improvements in Stock-Feeding Devices, of which the following is a specification, reference being had therein to the accompanying drawing.

This invention comprises a stock feeding device. While of general application, it is especially adapted for use in the feeding of hogs.

It is contemplated among other objects to produce a device of this kind wherein there will be provided a storage receptacle for feed, the arrangement being such that it will not be necessary to fill the hopper at short intervals and wherein the animals can get the kind and amount of any feed placed in the hoppers, according to the dictates of appetite.

Another object of the invention is to provide for a more uniform feeding of the material in the hopper to a trough which is associated therewith so that there will be no stoppage or blockading of the food in the hopper, a difficulty which has heretofore been frequently experienced with devices of the V-shaped type.

Still a further object of the invention is to arrange for a graduated feeding of the materials from the hopper to the trough and to this end the doors are secured to portions of the receptacle which are capable of adjustment so that the space between the bottom of the door and the bottom of the trough may be varied as circumstances require.

Other objects and advantages will in part be apparent and in part be brought out in the description which follows.

A drawing illustrating an embodiment of the device is hereto appended in which the following views are shown.

Figure 1 is a front elevation;

Fig. 2 is a vertical sectional view.

Referring specifically to the drawings 1 designates a back portion, 2 side portions, 5 and 3 a bottom portion, joined to form components of a receptacle or hopper 4. The sides 3 have extensions 5 joined to a bottom portion 6 which is preferably a continuation of the bottom of the receptacle, and joining 55 the underneath portion of said side extensions there is a portion 7 which constitutes

the front end of a trough or the like 8. The hopper is preferably provided with a partition 9 dividing it into compartments the front edge of said partition and of the sides 60 having stops or backing strips 10 between which there is slidably mounted front portions 11 of the hopper.

Means are provided for effecting an adjustment of these portions in the stops, and 65 as herein disclosed comprise a rod or the like 12 having tensioning means 13 to retain the slidable portions in the stops by tension. Upon the lower edges of each of the front portions 11 there is mounted a swinging 70 door 14 hingedly connected so as to have free movement inwardly toward the interior of the hopper and restrained against outward movement by a downwardly extended portion of certain of the stops 10.

Means are also provided for normally holding these doors in engagement with the stops and to this end springs 15 are shown arranged in connection with the hinges. By this arrangement, it will be noted that the 80 bottom portion 3 of the hopper is disposed tangentially to the arc produced by the internal swinging of the door as distinguished from structures wherein the floor follows parallel to the arc produced by the lower 85 portion of the door in its swinging movement. It has been found in practice that this aids materially in preventing clogging of the feed and produces an even feed from the hopper to the trough.

A cover portion 16 is also provided for the hopper and as here shown is hingedly secured to one of the sections.

While we have disclosed our invention in the embodiment herein set forth, it will be 95 understood that we do not wish to limit ourselves to the precise form of this disclosure as many changes may be made in the general construction and arrangement of the parts without departing from the principles 100 of the invention or sacrificing its chief advantages.

What we claim is:

A stock-feeding structure comprising bottom, side and back portions joined to form 105 a feed-receiving receptacle; backing strips arranged on the sides; stop members also arranged on the sides and spaced apart in parallelism from the backing strips to form guides; a front section slidably disposed in 110 the guides; means for maintaining the slid-able section at different heights in respect

to the bottom portion; a door secured to the front section and having its lower edge in spaced relation to the bottom of the trough and engageable with the stop members to limit its forward swinging movement; an extension on the bottom portion and projecting beyond the plane of the stop members, an upstanding member on the extension and arranged in spaced relation from the stop members and constituting, with the sides and bottom portions and the door, a trough in front of the door; the door normally lying at an angle to the vertical to maintain itself in engagement with the stop

members and swingable away from the up-standing member to increase the size of the opening between its lower edge and the bottom; and a cover member movably secured to one of the portions and extending beyond the vertical plane of the bottom extension 20 to protect the trough.

In testimony whereof we affix our signatures in presence of two witnesses.

HAROLD C. M. CASE.

WILBUR J. CARMICHAEL.
